COMBINED ROTARY INDEX AND MEMO SHEET HOLDER

Hildaur L. Nielsen, Metuchen, N.J., assignor to Zephyr
American Corporation, Long Island City, N.Y., a cor-
poration of New York

Filed May 8, 1969, Ser. No. 17,080

Term of patent 14 years

Int. Cl. D19—99

U.S. Cl. D74—2

FIG. 1

FIG. 2

FIG. 3

FIG. 4

FIG. 5

FIG. 1 is a front perspective view of a combined rotary index and memo sheet holder showing my new design as it appears with some of the tabs omitted for convenience of illustration;

FIG. 2 is a top view of the memo sheet holder as seen from the line 2—2 of FIG. 1;

FIG. 3 is an elevational view of the side of the combined rotary index and memo sheet holder opposite to the side thereof which is in view in FIG. 1;

FIG. 4 is a front elevational view of the combined rotary index and memo sheet holder; and

FIG. 5 is a rear elevational view of the combined rotary index and memo sheet holder.

I claim:

The ornamental design for a combined rotary index and memo sheet holder, as shown and described.
